UNITED STATES PATENT OFFICE.

EDWIN PRESTON, OF OAKLAND, CALIFORNIA.

BUILDING BLOCK.

1,418,168.

Specification of Letters Patent. Patented May 30, 1922.

Application filed August 2, 1920. Serial No. 400,581.

To all whom it may concern:

Be it known that I, EDWIN PRESTON, a citizen of the United States, and a resident of Oakland, county of Alameda, and State 5 of California, have invented a new and useful Building Block, of which the following is a specification.

My invention relates to building blocks and particularly to the hollow type made 10 of concrete or the like.

An object of the invention is to provide a building block which when disposed in a wall comprised of these blocks, will interlock and form a wind-break at each of its 15 junctures with the associated blocks, without the aid of a binding medium.

Another object of the invention is to provide a block which will permit of the blocks being interlocked in staggered relation.

20 The invention possesses other objects and features of advantage, some of which, with the foregoing, will be set forth in the following description of the preferred form of my invention which is illustrated in the 25 drawings accompanying and forming part of the specification. It is to be understood that I do not limit myself to the showing made by the said drawings and description, as I may adopt variations of the preferred 30 form within the scope of my invention as set forth in the claim.

Referring to said drawings:

Fig. 1 is perspective view of the block.

Fig. 2 is perspective view of the block 35 viewing it from a different angle than that of Fig. 1.

Fig. 3 is a vertical section of a number of the blocks set up.

The preferred embodiment of the block 2 40 of my invention is preferably in the form of a parallelepiped having its bases with unequal adjacent sides. The block as here shown is hollow and provided with a web 3 which extends from the middle of one side 45 wall 4 of the block to the other side wall 5.

Means are provided for interlocking the abutting ends of adjoining blocks when the latter are assembled in a building wall. Formed on the outer side of the end wall 7 50 of the block is a vertical rib 8 which preferably extends from the top to the bottom thereof. The other end wall 9 of the block is formed with a groove 11 which is aligned with and of the same shape as the rib 8.

When the blocks are properly assembled as 55 shown in Figure 3 the rib of one block will fit into the groove of the adjoining block thereby not only interlocking the end walls but providing an effective wind-break at the opening therebetween.

Means are also provided for effectively interlocking each block with the adjoining blocks above and below it. Formed upon 60 one of the bases or faces 12 and 13 of the block is a substantially continuous shoulder 65 14 which extends along the inner edges of the face but is spaced from the outer edges thereof. Although the drawings show the shoulder as being on the top face 12 of the block, it is to be understood that this is 70 merely for the purpose of illustration, as it is obvious that the block may be arranged in the wall of the building either with the shouldered face above or below. The bottom face 13 of the block is formed at its 75 inner edge with a depressed portion 15 which is aligned with and corresponds in shape to the shoulder 14. In order that the layers of blocks when assembled may lie in staggered relation, I omit the shoulders at 80 the middle of the side walls to form recesses 17 and 18 so that the undeformed portion 19 of the bottom faces of adjoining end walls of the next layer of blocks may fit therein, thereby firmly locking the blocks together 85 as well as in position. To augment the locking feature just referred to, the web 3 preferably extends to the bottom face so that when the blocks are assembled the lower end of the web will fit into the space between the 90 shoulders of adjoining blocks of the layer above or below as the case may be. It will be noted that the top 21 of the web 3 is flush with the face 12 or bottom of the recesses so that a large bearing is provided for 95 supporting the bottom faces of the end walls of the blocks when the latter are assembled.

I claim:

A hollow building block comprising end and side walls having top and bottom faces, 100 a web parallel to and of the same thickness as said end walls arranged to connect said side walls together whereby a pair of transversely aligned openings are formed in said block, a substantially continuous shoulder 105 formed along each of the upper edges of said openings except the edge defined by said web, the terminating faces of said

shoulders being parallel to and in the plane of the adjacent face of said web, and a continuous shoulder extending along the bottom edges of said block spaced from the inner sides of said openings and having its lower face flush with the bottom of said web.

In testimony whereof, I have hereunto set

my hand at Oakland, California, this 19th day of July, 1920.

EDWIN PRESTON.

In presence of—

L. L. M. SALSBURY,

F. L. PRESTON.
